UNITED STATES PATENT OFFICE.

WILLIAM F. THOMPSON, OF CLEVELAND, OHIO.

DUPLEX CONDUCTOR FOR ROLLING-MILLS.

SPECIFICATION forming part of Letters Patent No. 391,664, dated October 23, 1883.

Application filed June 10, 1887. Serial No. 240,908. (No model.)

To all whom it may concern:

Be it known that I, WILLIAM F. THOMPSON, of Cleveland, in the county of Cuyahoga and State of Ohio, have invented a certain new and Improved Duplex Conductor for Use in Combination with Wire-Rod Mills; and I do hereby declare that the following is a full, clear, and complete description thereof.

The nature of my invention relates to an improved dualistic system of conductors or guides used in connection with wire-rod mills, to facilitate not only the operation of rolling wire rods, but also largely increasing the capacity of the mill and causing less waste of stock than in the ordinary operations.

That the improvement may be more fully seen and understood by those skilled in this art, reference will be had to the annexed specification and the accompanying drawings, of which—

Figure 1, Plate 1, is an elevation view of a pair of coupled three-high rolls provided with a dual guiding or conducting mechanism from one set of rolls to another. Fig. 2 represents a horizontal section of the rolls on line *x x* and a plan view of the main part of the conducting apparatus in connection with the rolls. Fig. 3, Plate 2, is a vertical section in line *x' x'*, Fig. 1. Fig. 4 is also a vertical section on line *y y*. Enlarged Fig. 5 is a face view of a detached section of said mechanism. Enlarged Fig. 6 is an end view of one of the conducting-pipes with its flaring mouth, detached from the mill mechanism or appliances.

Like letters of reference refer to like parts in the several views.

In the drawings, *A* and *A'* represent a pair of mills of three-high rolls arranged in line with a train of other mills, (not shown in the drawings,) adapted for the rolling and reduction of wire rods. On one or both ends of this train of mills is arranged a set of three-high pinions, (not shown,) which receive motion from any suitable motor, and are mounted in 45 housings of the same construction as those used in connection with the rolls. The spindles *B* of the rolls *C C'* are provided with a fluted extension, *a*, (technically known as "warblers," and seen in Figs. 1 and 2,) over 50 which the thimbles *D* are fitted to transmit motion from one mill to another and primary rotation from the said pinions to the first mill.

Of these mills or three-high rolls only two rolls are grooved for the gradual reduction of wire rods. The third roll is a dummy or blank one, which alternately runs either on top or bottom of the respective grooved rolls, for a purpose as hereinafter shown. These mills in pairs are arranged to co-operate one with another by means of a duplex conducting mechanism, as seen in Figs. 1 and 2, which consists of a duplex semicircular grooved conductor, *E*, and the guide-pipes *F*, *G*, and *H*. On one side of every mill-housing a groove, *I*, is formed, in which the slotted bar *J* is adjusted and held in the required position for the purpose of supporting the guide-holders *K* and *L*, Figs. 3 and 4. By means of the slot within the bar *J* said holders can readily be shifted in a horizontal direction without removing the bolt *M* to adjust the guide-pipes in line with the respective grooves of the rolls. The pipes *F* guide the wire rods (after passing through the rolls of the mill *A*) either into the outer or inner channel, *d d*, of the conductor *E* above referred to, and for that purpose they are made tapering and closely held up (see Fig. 3) to the bite of said rolls, that the wire rods may move freely and easily enter the pipes, but leading the same through an opening much smaller than the entrance. By this means the tendency is to discharge the wire in a straight course into the conductor *E*, Figs. 2 and 3. The pipes *F* are securely connected within and by the guide-holder *K* by means of a set-screw, *c*, as seen in Figs. 1 and 3, and in the enlarged Fig. 5, which illustrates a face view of the same.

In Fig. 5 it can readily be seen that the cover *K'* is constructed to fit over the lugs *b*, attached to the lower part of said holder *K*, and that by means of the set-screw *c* a fixed connection of the pipe *F*, the guide-holder *K*, and cover *K'* is had. In this way no extra means for the smaller end of the pipes *F* are required to hold the same within the grooves or channels *d d* of the conductor *E*, as seen in Figs. 2 and 3.

The conductor proper begins at the point where the bifurcated channels *d d* unite into a duplex conductor at *F'*. The inner sides of the channels converge into one partition, *f*, and so form a duplex curved conductor with a central partition for the division thereof, as seen in Fig. 2. This conductor *E* is supported

by two or more standards, N N, as seen in Figs. 1 and 3. The lower part of said standards is secured to the floor, and the upper part to the base of the conductor, a slot, *n'*, in one 5 or both parts, and having screw-bolts, which arrangements allow of a vertical variation to adjust and hold the conductor in such position as the rolls may determine. In Fig. 1 only a part of the base of said standards is shown, 10 so as not to hide other parts from view.

As aforesaid, the conductor in part is a duplex semicircle, which at the terminus E' bifurcates into the guides *e e*, to serve as means for the attachment of the pipes G G, 15 and to direct the rod in line to the flaring mouths G' G' thereof. The lower sides of the flaring mouths G' G' of the pipes G G are provided with a slotted hole, as seen at *f'*, Fig. 2, for lateral adjustment in connecting the 20 pipes with the conductor. The pipes H H, as well as the pipes G G, consist of halves *i j* and *l m*, divided longitudinally, as seen in Figs. 3, 4, and 6. The halves are hinged together at *g*, and provided with a spring-latch, 25 *g'*, and lug *h*, as seen in Figs. 2 and 6. The pipes G and H are made in sections, for the reason that the pipe H will wear out at the end toward the rolls much sooner than the rest of the pipe; hence the cost of replacing the 30 pipe H is much less than the cost would be for the whole length from the conductor E to the liners O O of the guide-holders L L.

To provide for the opening of the pipes G and H by means of the lids, as before stated, 35 is an essential feature of this invention, in so far as a ready admission to the interior of these pipes may be obtained in case of accident—such as the breaking or bending of the rods in the passage through the conductor and 40 guide-pipes—for the removal of such obstructions. The rods are fed in between the grooved rolls C C of the mill A, as seen in Figs. 2 and 3, and their course when leading said rolls is directed by the guide-pipes F F and the channelled semicircular conductor E, in which the 45 wire rods while yet in a heated state are bent to follow the line of said conductor to and through the pipes G H and the guide-liners O O, wherein the rods are properly introduced 50 for reduction between the rolls of the mill A'. The flaring mouths of the pipes G afford an easy and accommodating communication with the conductor E, which is especially essential as soon as the rods are stretched or forced 55 over the conductor into the bifurcated guides *e e* when the train of rolls are active, as the flaring mouths tend to receive and direct a diverging rod in line to the pipes.

The guide-holders L L are attached to the 60 bar J in like manner as the holder K. The pipes H rest on the plain front part of these holders or supporters and extend in between the flaring guide-liners O, which are secured in place by the set-screws *h'*.

65 In Fig. 1 the conductor E is shown as connected with the upper and lower pair of rolls of the mills A and A', which is necessary in

order to lead the rods between rolls turning in opposite direction to each other, that the wire can enter and leave the rolls, as indicated in Figs. 3 and 4. The blank roll C' is only used in co-operation for the transmission of power from one roll to another in a proper direction.

By the means heretofore in use the feeding 75 or entering of a new rod had to be delayed until the entire length of the preceding rod was taken through the reducing-rolls, thus greatly impairing the efficiency and capacity 80 of the mills.

By the construction and arrangement of the improved mechanism herein described no delay need occur in waiting with the feeding of one rod until the other has completely been drawn through by the reducing-rolls, for the 85 reason that the pipes and channels of this duplex conductor will lead two rods simultaneously from the grooves of the mill A, thereby greatly increasing the capacity of the rolls or 90 mill.

If a rod on passing through the pipes G and H becomes bent, broken, or twisted, thereby forming an obstruction within said pipes, the lid of the respective pipe is then readily opened and the obstruction removed, while the rod in 95 the adjoining groove or pipe can be drawn along between the rolls independent of the interruption in the other circuit.

This improvement reduces the liability of 100 the said rods bending or breaking in the transit from the rolls A to the rolls A', as the conductor and guide-pipes C H with the flaring mouths cause a safe guidance of the rods from one set of rolls to the other, as before stated; hence there is less waste of stock and an increased capacity and a higher percentage of 105 results than by the ordinary means.

The described mechanism of the conductor and attachments, in connection with the rolls, 110 may be so enlarged and arranged as to lead and conduct more than two rods simultaneously from one set of rolls to the following reducing-rolls in essentially the same way as the transit of two rods from the rolls A to and through the rolls A', before set forth.

115 What I claim as my invention, and desire to secure by Letters Patent, is—

1. In combination with a wire-rod mill or rolls, a duplex conductor consisting of semi-circular channelled circuits having attached thereto guide-pipes arranged in co-relation with the grooves of the rolls to lead and guide the rods while in a heated state from and into the rolls, constructed substantially as described, and for the purposes set forth.

2. The guide-pipes G H, arranged in sections and provided with lids or covers, in combination with the duplex conductor and the train of rolls A A', substantially as described, and for the purpose set forth.

3. The combination, with a train of wire-rod rolls, of a duplex conductor with guide-pipes F at one end and at the other guide-pipes G H, arranged in connected sections,

having flaring mouths in open relation with the circuits of said conductor and provided with covers or lids, constructed and arranged substantially as described, and for the purpose 5 set forth.

4. The combination, with a train of rod-rolls, of guide-holders K, caps K', with pipes F, jointly secured together by means of the set-screw c, arranged as set forth and in co-oper-

ating relation with the duplex conductor and 10 pipes G H, substantially as and for the purpose set forth.

In testimony whereof I affix my signature in presence of two witnesses.

WM. F. THOMPSON.
